UNITED STATES PATENT OFFICE

LEONARD SCOTT FENWICK, OF TORONTO, ONTARIO, CANADA.

NON-REFILLABLE BOTTLE.

No. 857,281.

Specification of Letters Patent.

Patented June 18, 1907.

Application filed December 3, 1906. Serial No. 346,138.

To all whom it may concern.

Be it known that I, LEONARD SCOTT FENWICK, of the city of Toronto, in the county of York, in the Province of Ontario, Canada, 5 have invented certain new and useful Improvements in Non - Refillable Bottles, of which the following is the specification.

My invention relates to improvements in non-refillable bottles having closing devices 10 of the kind provided with an internal sleeve shaped to fit the neck of the bottle and adapted to engage with a shoulder or in a groove or recesses formed in the said neck, a hollow valve provided with a tapered lower 15 end, and a protecting cap designed to fit into the top end of the sleeve and formed with a hollow depending stem designed to extend down into the interior of the valve when in its normal position.

According to my invention I provide the 20 valve with guide-ribs to guide it within the sleeve and I construct the cap, so that it can be spread or formed to engage the groove, shoulder or recesses in the bottle neck with 25 which the sleeve engages. I also provide perforations in the flange formed around the stem of the cap and a spring between the latter and the valve.

Figure 1, is a sectional perspective view 30 showing the neck portion of a bottle and my improved device for preventing the non-refilling of the same. Fig. 2, is a similar view showing the device provided with an alternative form of protecting cap. Fig. 3, is a detail of the internal sleeve adapted to fit the 35 neck of the bottle. Fig. 4, is a detail of the valve. Fig. 5, is a detail of the protecting cap.

In the drawings like letters of reference indicate corresponding parts in each figure.

A is the internal sleeve, which is adapted to fit the neck of the bottle being in the form shown or any other desired form. The bottom of the sleeve, however, is provided with 45 a tapered reduced portion A' leaving a narrow shoulder A² surrounding the same at the top. The upper end of the sleeve flares outwardly at A³ and is by any suitable instrument pressed into the groove B formed in 50 the bottle and necessarily under the shoulder forming the top side of the groove.

C is the valve, which is closed at the bottom and is hollow and tapered as shown and

formed with guiding ribs C', which are designed to guide the valve in its longitudinal 55 movement within the cylindrical portion of the sleeve A.

D is the protecting cap or cover for the device, which is formed as shown in Fig. 1, with an outwardly extending flange D', which is 60 spread to fit in the groove B in the neck of the bottle and under the shoulder formed thereby. The protecting cap D is provided with a perforated upwardly extending central portion D² from the top of which depends the hollow stem D³, which is provided with a hole D⁴ near or at the bottom and within the valve C.

2 is the spiral spring, which extends between the cap D, the stem D³ of which it surrounds, and the valve C as indicated. The spring 2 is designed to force the valve on its seat when the bottle is partially tipped, that is to say when it is more on its side but is not of sufficient strength to force the valve on its 75 seat when the bottle is in the inverted position.

If the spring were not provided there might be a liability of the valve not closing when the bottle is on its side and the spring 80 insures of the valve closing should it be attempted to fill the bottle when it is on its side. Of course, the valve would naturally float up if the bottle were inverted and the spring is weak enough so that it will not support the weight of the valve when the liquid 85 is being poured out.

In Fig. 2, I show the upper portion of the protecting cap D substantially reversely formed to that shown in Fig. 1, such protecting cap in this case being formed with the upwardly extending central portion D⁵ of a greater diameter than the hollow stem and perforated as shown, the horizontal portion D⁶ at the top, the depending portion D⁷ 95 adapted to fit the neck of the bottle and provided with lips D⁸ punched out of the flange D' and fitting underneath the shoulder in the neck and the inwardly extending flange D⁹.

The object of both the protecting caps 100 shown in Figs. 1 and 2 is to prevent the insertion of wires by which the free movement of the valve might possibly be prevented, and yet allow of the free escape of the liquid.

I shall now describe the utility of my device.

Should it be desired to pour out the liquid the bottle being tilted the valve C will pass off its seat being held in proper position in its longitudinal movement in the neck by the guides C'. The liquid will pass out around the annular space between the valve and the cylindrical portion of the sleeve A' and through the perforated flange D². The hole D⁴ in the hollow stem will permit of the air 10 to pass inwardly so that the free pouring out of the liquid is facilitated, such hole preventing the liquid from passing down quickly and filling the space around the stem and possibly throwing back the valve on its seat 15 when the liquid is being poured out.

Should it be desired to refill the bottle the pressure of the liquid in no matter what way the bottle may be inverted would float the hollow valve quickly up on its seat, the air 20 forced in by the liquid being facilitated in its passage to the valve by the hole D⁴, so that before the liquid can reach the opening between the valve and its seat it will have, through the medium of the air in the valve 25 floated the valve back to its seat. Should, however, the bottle be in a substantially horizontal position or a tilted position the preponderance of the weight of the liquid will force the valve back quickly on to its seat and thereby prevent the liquid from 30 passing into the bottle and this it will be understood would arise from the fact of the larger area of the valve as compared with the annular space between it and the sleeve. 35 The material, which I make the device of is preferably aluminium although, of course, any other suitable material may be used.

Although I show lips D⁸, in Fig. 2, it will be understood that such lips may be used in

the form shown in Fig. 1, instead of flaring 40 the top of the internal sleeve.

What I claim as my invention is:

1. In a non-refillable bottle, in combination a sleeve adapted to fit the neck of the bottle and provided with a reduced tapered 45 lower portion, a hollow imperforate valve provided with a suitable bottom and tapered lower portion, guiding ribs upon the valve and a protecting cap fitting the upper portion of the sleeve and suitably secured in place 50 and provided with a depending stem extending into the valve and having a hole therein, the stem of the valve having perforations in the flange surrounding the same and the sleeve being adapted to engage a groove in 55 the neck of the bottle as and for the purpose specified.

2. In a non-refillable bottle, in combination a sleeve adapted to fit the neck of the bottle and provided with a reduced tapered 60 lower portion, a hollow imperforate valve provided with a suitable bottom and tapered lower portion, guiding ribs upon the valve and a protecting cap fitting the upper portion 65 of the sleeve and suitably secured in place and provided with a depending stem extending into the valve and having a hole therein, the stem of the valve having perforations in the flange surrounding the same and the sleeve being adapted to engage a 70 groove in the neck of the bottle, and a spiral spring extending from the cap to the bottom of the hollow valve as and for the purpose specified.

LEONARD SCOTT FENWICK.
